UNITED STATES PATENT OFFICE.

GILBERT RIMMER, OF NOTTINGHAM, AND AUSTIN YOUNG HOY, OF LONDON, ENGLAND,
ASSIGNORS TO SULLIVAN MACHINERY COMPANY, OF CHICAGO, ILLINOIS, A COR-
PORATION OF MASSACHUSETTS.

MINING APPARATUS.

Application filed January 18, 1926, Serial No. 32,042, and in Great Britain January 19, 1925.

This invention relates to improvements in mining apparatus, particularly coal cutting machines and trolleys therefor. The invention has for its main object to enable a mining machine of the swinging jib type to be used for cutting in any of two or more planes. More particularly the invention has for its object to provide means whereby a self-contained mining machine of a type adapted to slide upon a surface thereof over a mine bottom may be truck mounted in such a manner that it can be rotated about its longitudinal axis relatively to the truck to alter the plane of cut of the swingable cutting mechanism carried by the said machine. The invention also aims to provide means for effecting truck propulsion from the motor in the machine and for adjusting the machine relatively to the truck by the said motor.

The present invention comprises a trolley or truck that is so constructed as to receive the machine and to retain such machine in different angular positions into which it is adjustable by rotation about its longitudinal axis relatively to the trolley in such manner as to alter the position in space of the cutting plane of the cutters.

The invention also comprises the combination of a coal-cutting machine of the swinging jib type, a trolley having upon it a mounting which is a cylindric trough or "virtual trough" with its axis parallel to the length of the machine, and means secured to the machine and projecting into said trough or virtual trough to constitute a trunnion for the machine.

By the term "virtual trough" is meant a mounting, the bearing-surface of which may be constituted, for example, by a plurality of rollers or other anti-friction members which are so arranged that those portions of their surfaces which are engaged by the means aforesaid are arranged to lie on the curve of an imaginary trough which will prevent the trunnion from dropping during its rotation.

According to a feature of the invention, there is combined with the trunnion and the trough or virtual trough an endwise movable bolt having its bearing in one of them and being capable of movement into and out of corresponding holes in the other, and

of being actuated from one end of the machine. The holes may be disposed angularly apart from one another and the bolt engaged by its own bearing can also be engaged with one or other of these holes to lock the machine securely in various positions to which it has been rotatably adjusted about the longitudinal axis thereof.

According to a further feature of the invention there is provided the combination with the trunnions of flanged claws secured on the trolley and overlapping the trunnions in opposite directions from opposite sides thereof, and means for operating the claws, for example, a single bolt in screw-threaded engagement with said claws. These claws when in engagement with the trunnions serve to prevent the machine from separating from the trolley, but when they are disengaged from the trunnions the machine is free to be lifted off the trolley.

Other objects and features of the invention will be apparent from the following description of forms of apparatus constructed in accordance with the invention.

In the accompanying drawings—

Figure 1 is a diagrammatic end elevation of a coal-cutting machine and trolley according to this invention.

Figure 2 is a similar view showing a modified construction;

Figure 3 is a side elevation of one preferred construction of machine and trolley according to this invention;

Figure 4 is a plan of the trolley from Figure 3 with the machine removed, and

Figure 5 is a sectional end elevation on the line 5—5 of Figure 3.

Like reference numerals refer to like parts throughout the drawings.

Referring first to Figure 1, it will be seen that the trolley 1 is provided with a mounting 2 in the form of a trough and to the underside of the coal-cutting machine 3, of a type hereinafter mentioned, there is detachably secured as by suitable screws, bolts or the like a complementarily curved attachment 4 which extends also over one lateral surface of the machine. The machine 3 may be readily detached from the attachments 4 and dismounted from the trolley. This attachment constitutes a trunnion for the machine. The attachment is such that it, with

the machine, may be revolved in the trough secured to the trolley about the longitudinal axis of the machine so that the plane of the swingable jib or cutter bar, indicated by 5, may be turned to any position in space from a horizontal to a vertical position, the extension of the attachment around one lateral surface of the machine enabling a full movement of 90° to be obtained. It will be understood that when the jib lies in the vertical plane, as shown in chain-dotted lines, the machine can be used for shearing.

In place of the trough-mounting above described a plurality of rollers may be used 15 to bear against the cylindric attachment portion 4 borne by the machine. Alternatively, as shown in Figure 2, the machine itself is provided with rollers 6 carried by the attachment 4. These rollers engage the trough 20 2 on the trolley and constitute a virtual trunnion.

In both of the above-described constructions a stop 7 on the trolley is arranged to engage the machine when in its horizontal 25 position and limit its movement in one direction. Any suitable means, such as hereinafter described, may be employed to lock the machine securely in its horizontal and vertical positions or in any intermediate 30 position if this is desired.

Referring now to Figures 3, 4 and 5, it will be seen that the machine 3 is provided with a pair of trunnions constituted by T-section attachments 4, (Figure 3) each of 35 which rests on a pair of rollers 8 rotatably mounted in a cradle 9 secured to the trolley 1 and forming a virtual trough or bearing for the trunnion. The arrangement of these rollers is clearly shown in Figure 5, from 40 which it will be observed that the two rollers for each trunnion are so spaced that the bearing surface of the trunnion rests on them both throughout the rolling movement of the machine from its horizontal to its 45 vertical position and vice versa.

In order to lock the machine in either of its adjusted positions two sliding bolts 10 are provided, each of which engages holes 11 in the upstanding lugs 12 on the cradle 50 and passes through a hole in the attachments 4. Two such holes are shown at 13 in Figure 5 and it will be understood that another hole 13 lies behind and in line with the hole 11. As shown, the bolts can be manipulated 55 separately from opposite ends of the machine but, if desired, a single long bolt extending to one end of the trolley and passing through both trunnions may be provided.

The arrangement of the trunnions in the 60 troughs is such that the machine can be lifted bodily from the trolley when desired, and is also such as to prevent endwise movement of the machine relatively to the trolley. To prevent the machine from accidentally 65 separating from the trolley at any time there

are provided, in combination with each trunnion, two flanged claws 14 travelling above flats 15 on the cradle 9, and overlapping the flanges of the T-section attachment 4 in opposite directions from its opposite sides as 70 clearly shown on one of the trunnions in Figure 3. These claws are engaged one with the other by a single right- and left-handed screw-bolt 16 which is supported in a sleeve 17 on the cradle. The bolt is manipulated to 75 secure or release the machine by means of a key or spanner which may be engaged with the head 20.

To prevent the machine from shifting endwise there are abutments 18 and 19 formed as shoulders on the cradle and trolley respectively; against these the end faces of the trunnions bear.

The rotation of the machine about its longitudinal axis in the trolley can be effected manually, if desired, or it may be effected mechanically. The machine shown in Figure 3 is of the kind described in the specification of one Morris P. Holmes Ser. No. 619,839, filed Feb. 19, 1923, and comprises an elongated generally rectangular body normally adapted to slide on its bottom surface 3^a directly on the mine bottom and within which the usual driving motor is housed and carrying cutting and feeding 90 mechanisms driven by this motor. The cutter bar 5 is pivotally mounted on this body for swinging movement relative thereto as clearly described in the above mentioned application.

The machine also has a driving-member in the form of a sprocket-wheel 21 for the purpose of actuating the flexible feeding means of the machine herein preferably a feed chain 21^a. This wheel is disposed at one end of the machine on a horizontal shaft 22 which is driven by the motor of the machine. This shaft also carries loose on it a chain-sprocket 23 provided on one side with dog-clutch teeth 24 and an operating 100 collar 25 whereby it may be moved into and out of engagement with the teeth 26 on the member 27 fast on the shaft. When the dog clutch is released the sprocket-wheel 21 is adapted to draw in the feed chain 21^a which 105 is connectible in a suitable manner to the cutter bar 5 as shown in Fig. 3 to swing the latter about its pivot relative to the machine body. When the dog-clutch is engaged, as shown, the drive from the motor is transmitted by way of an endless chain 28 and a sprocket 29 on the shaft 30 to the track 110 wheels 31 through the reversible bevel-gear-drive 32 and chain-gear 33. The trunnions are made to be co-axial with the rotational 115 axis of the shaft 22 and thus when the machine is turned from one position to another on its trunnion the drive to the trolley is unaffected as the distance between the driving shaft on the machine and the driven 120

130

shaft on the trolley remains the same and no adjustment of the chain 28 is required. If the sprocket 29 or the chain 28 be locked and the motor in the machine be actuated 5 then the endless chain being unable to move, the reaction of the motor in the machine against the resistance of the chain will cause the machine itself to turn about its longitudinal axis in its bearings on the trolley. Any suitable form of lock-clutch 10 or brake may be provided for locking the sprocket 29 and in the drawings a detent device 34 is shown which can be engaged with the sprocket to hold it stationary when it 15 is desired to swing the machine.

Instead of the dog-clutch arrangement above described for disengaging the sprocket 23 from the power shaft 22, the chain 28 may be arranged to be readily removable 20 from its sprockets so that the drive to the track wheels may be disconnected when required.

The trolley is provided with a track-brake 35, and a band-brake 36 is associated with 25 the jib to enable the latter to be more readily controlled when slewing in the vertical plane. These brakes are provided with controls 37 and 38 respectively which are both accessible from one end of the machine. 30 The control 37 for the track-brake is connected with a rod 39 having a screw-threaded portion 40 engaging a nut-portion pivotally mounted on a depending arm 41 fast on a transverse shaft 42 pivotally mounted on the 35 truck and carrying arms 43 each fixed thereto and pivotally connected at 44 with a shank 45 operatively connected with the brake 35. Thus it will be seen that the arrangement of the arms 41 and 43 on the shaft 42 constitute a bell-crank lever which can be operated to raise or lower the brake 35 relatively to the track rails by means of the screw 40, which screw also serves to lock the brake in its on or off position.

45 It will be understood that the constructional embodiments herein described are given by way of example only and that modifications may be made therein without departing from the spirit of the invention 50 or the scope of the appended claims.

We claim:

1. In a mining apparatus, a truck, a self-contained mining machine of a type adapted to slide upon a surface thereof over a mine bottom, and means for adjustably supporting said machine on said truck for rotation about a horizontal longitudinal axis including 55 arcuate guiding means secured to one of the same and cooperating guiding means secured to the other.

2. In a mining apparatus, a truck, a self-contained mining machine of a type adapted to slide upon a surface thereof over a mine bottom, and means for adjustably supporting 60 said machine on said truck including

arcuate guiding means secured to one of the same and on the other a plurality of co-operating rollers rotatable on axes disposed in a surface coaxial with the centre from which said arcuate guiding means is struck. 70

3. In a mining apparatus, a truck, a self-contained mining machine of a type adapted to slide upon a surface thereof over a mine bottom, and means for adjustably supporting said machine on said truck for rotation 75 about a horizontal longitudinal axis including arcuate guiding means secured to the machine and cooperating guiding means carried by the truck.

4. In a mining apparatus, a truck, a self-contained mining machine of a type adapted to slide upon a surface thereof over a mine bottom, and means for adjustably supporting said machine on said truck for rotation 80 about a horizontal longitudinal axis including arcuate guiding means secured to the machine and a plurality of cooperating rollers carried by said truck and cooperating with said guiding means.

5. In a mining apparatus, a truck, a self-contained mining machine of a type adapted to slide upon a surface thereof over a mine bottom, arcuate guiding members secured to said mining machine for supporting the latter for rotation about its longitudinal axis, 90 and cooperating rollers mounted on said truck at opposite sides of a vertical longitudinally extending plane passing through the centre of mass of the machine.

6. In a mining apparatus, a truck, a self-contained mining machine of a type adapted to slide upon a surface thereof over a mine bottom, arcuate guiding members secured to said mining machine for supporting the latter for rotation about its longitudinal axis, 100 cooperating rollers mounted on said truck at opposite sides of a vertical longitudinally extending plane passing through the centre of mass of the machine, and means on said truck intermediate said rollers for 105 maintaining said arcuate guiding means against vertical displacement with respect to said rollers.

7. In a mining apparatus, a truck, a self-contained mining machine of a type adapted 115 to slide upon a surface thereof over a mine bottom, said mining machine having a feed operating member rotatable upon a longitudinally extending axis, and means for permitting adjustment of said machine about 120 an axis coincident with the axis of said feed operating member including means for supporting said machine on said truck including arcuate guiding means secured to one of the same and cooperating guiding means secured 125 to the other.

8. In a mining apparatus, a truck, a self-contained mining machine of a type adapted to slide upon a surface thereof over a mine bottom, said mining machine having a feed 130

operating member rotatable upon a longitudinally extending axis, and means for permitting adjustment of said machine about an axis coincident with the axis of said feed 5 operating member including means for supporting said machine on said truck including arcuate guiding means secured to one of the same and on the other a plurality of cooperating rollers rotatable on axes disposed in 10 a surface coaxial with the centre from which said arcuate guiding means is struck.

9. In a mining apparatus, a truck, a self-contained mining machine of a type adapted to slide upon a surface thereof over a mine 15 bottom, said mining machine having a feed operating member rotatable upon a longitudinally extending axis, and means for permitting adjustment of said machine about an axis coincident with the axis of said feed 20 operating member including means for supporting said machine on said truck including arcuate guiding means secured to the machine and cooperating guiding means carried by the truck.

25 10. In a mining apparatus, a truck, a self-contained mining machine of a type adapted to slide upon a surface thereof over a mine bottom, said mining machine having a feed operating member rotatable upon a longitudinally extending axis, and means for permitting adjustment of said machine about an axis coincident with the axis of said feed 30 operating member including means for supporting said machine on said truck including arcuate guiding means secured to the machine and a plurality of cooperating rollers carried by said truck and cooperating with 35 said guiding means.

40 11. In a mining apparatus, a truck, a self-contained mining machine of a type adapted to slide upon a surface thereof over a mine bottom and having midway between the top and bottom and between the lateral edges thereof a feed operating member, and means 45 permitting adjustment of said machine upon an axis coincident with the axis of said feed operating member including means for adjustably supporting said machine on said truck including arcuate guiding means secured to one of the same and cooperating 50 guiding means secured to the other.

55 12. In a mining apparatus, a truck, a self-contained mining machine of a type adapted to slide upon a surface thereof over a mine bottom and having midway between the top and bottom and between the lateral edges thereof a feed operating member, and means 60 permitting adjustment of said machine upon an axis coincident with the axis of said feed operating member including means for adjustably supporting said machine on said truck including arcuate guiding means secured to one of the same and on the other a plurality of cooperating rollers rotatable on 65 axes disposed in a surface coaxial with the

centre from which said arcuate guiding means is struck.

13. In a mining apparatus, a truck, a self-contained mining machine of a type adapted to slide upon a surface thereof over a mine 70 bottom and having midway between the top and bottom and between the lateral edges thereof a feed operating member, and means permitting adjustment of said machine upon an axis coincident with the axis of said feed 75 operating member including means for adjustably supporting said machine on said truck including arcuate guiding means secured to the machine and cooperating guiding means carried by the truck.

80 14. In a mining apparatus, a truck, a self-contained mining machine of a type adapted to slide upon a surface thereof over a mine bottom and having midway between the top and bottom and between the lateral edges 85 thereof a feed operating member, and means permitting adjustment of said machine upon an axis coincident with the axis of said feed operating member including means for adjustably supporting said machine on said truck including arcuate guiding means secured to the machine and a plurality of cooperating rollers carried by said truck and cooperating with 90 said guiding means.

95 15. In a mining apparatus, a truck, a self-contained mining machine of a type adapted to slide upon a surface thereof over a mine bottom, arcuate guiding members secured to said mining machine for supporting the latter for rotation about its longitudinal axis, 100 cooperating guiding rollers mounted upon said truck, and means on said truck cooperating with said arcuate members to prevent longitudinal movement of said machine on said truck in either direction.

105 16. In a mining apparatus, a truck providing means forming a cradle, a self-contained mining machine of a type adapted to slide upon a surface thereof over a mine bottom, arcuate guiding means secured to said mining machine and supported in said cradle whereby said mining machine may be rotated about its longitudinal axis through substantially a quadrant, and means for rigidly connecting said cradle and said arcuate guiding means to maintain said mining machine in different adjusted positions.

110 17. In a mining apparatus, a truck providing means forming a cradle, a self-contained mining machine of a type adapted to slide upon a surface thereof over a mine bottom, arcuate guiding means secured to said mining machine and supported in said cradle whereby said mining machine may be rotated about its longitudinal axis through substantially a quadrant, and means including a bolt device for rigidly connecting said cradle and said arcuate guiding means to maintain said mining machine in different adjusted 115 positions.

18. In a mining apparatus, a truck providing means forming a cradle, a self-contained mining machine of a type adapted to slide upon a surface thereof over a mine bottom, arcuate guiding means secured to said mining machine and supported in said cradle whereby said mining machine may be rotated through substantially a quadrant, and means including a bolt device reciprocable longitudinally of said machine for rigidly connecting said cradle and said arcuate guiding means to maintain said mining machine in different adjusted positions.
19. In a mining apparatus, a truck, a self-contained mining machine of a type adapted to slide upon a surface thereof over a mine bottom, means for adjustably supporting said machine on said truck for rotation about a horizontal longitudinal axis including arcuate guiding means secured to the machine and cooperating guiding means mounted on the truck supporting said arcuate guiding means, and means cooperating with said arcuate guiding means for maintaining the latter in operative relation to said cooperating guiding means.
20. In a mining apparatus, a truck, a self-contained mining machine of a type adapted to slide upon a surface thereof over a mine bottom, means for adjustably supporting said machine on said truck for rotation about a horizontal longitudinal axis including arcuate guiding means secured to the machine and cooperating guiding means mounted on the truck supporting said arcuate guiding means, and means cooperating with said arcuate guiding means for releasably maintaining the latter in operative relation to said cooperating guiding means.
21. In a mining apparatus, a truck, a self-contained mining machine of a type adapted to slide upon a surface thereof over a mine bottom, means for adjustably supporting said machine on said truck for rotation about a horizontal longitudinal axis including arcuate guiding means secured to the machine and cooperating guiding means mounted on the truck supporting said arcuate guiding means, and means cooperating with said arcuate guiding means for releasably maintaining the latter in operative relation to said cooperating guiding means.
22. In a mining apparatus, a truck, a self-contained mining machine of a type adapted to slide upon a surface thereof over a mine bottom, means for adjustably supporting said machine on said truck including arcuate guiding means secured to the machine and cooperating guiding means mounted on the truck supporting said arcuate guiding means, and means cooperating with said arcuate guiding means for releasably maintaining the latter in operative relation to
- said cooperating guiding means including oppositely longitudinally moving jaws cooperating with said arcuate guiding means.
23. In a mining apparatus, a truck, a self-contained mining machine of a type adapted to slide upon a surface thereof over a mine bottom, means for adjustably supporting said machine on said truck including arcuate guiding means secured to the machine and cooperating guiding means mounted on the truck supporting said arcuate guiding means, and means cooperating with said arcuate guiding means for releasably maintaining the latter in operative relation to said cooperating guiding means including oppositely longitudinally moving jaws cooperating with said arcuate guiding means and screw means for causing said jaws to approach and move away from each other.
24. In a mining apparatus, a truck, a self-contained mining machine of a type adapted to slide upon a surface thereof over a mine bottom and having a feed operating member rotatable upon a longitudinally extending axis, means for adjustably supporting said machine on said truck for rotation on a longitudinal axis, a truck propulsion member including a truck driving shaft rotatable upon an axis parallel to the axis of said feed operating member and mounted on said truck, and operative connections between said feed operating member and said shaft.
25. In a mining apparatus, a truck having running gear, a self-contained mining machine of a type adapted to slide upon a surface thereof over a mine bottom, means for adjustably supporting said machine on said truck for rotation on a horizontal longitudinal axis, and reversible driving gearing for said running gear driven by said mining machine and disposed beneath and between the ends of the latter.
26. In a mining apparatus, a truck having running gear, a self-contained mining machine of a type adapted to slide upon a surface thereof over a mine bottom, means for adjustably supporting said machine on said truck for rotation on a horizontal longitudinal axis, and reversible driving gearing for said running gear driven by said mining machine and disposed beneath and between the ends of the latter, said reversible driving gearing including reversely rotating bevel gears rotating on a transverse axis and selectively operative as the driving element.
27. In a mining apparatus, a truck having running gear, a self-contained mining machine of a type adapted to slide upon a surface thereof over a mine bottom, means for adjustably supporting said machine on said truck for rotation on a horizontal longitudinal axis, and reversible driving gearing for said running gear driven by said

mining machine and disposed beneath and between the ends of the latter, said reversible driving gearing including reversely rotating bevel gears rotating on a transverse axis and selectively operative as the driving element and a longitudinally extending shaft having a bevel pinion meshing with said bevel gears.

28. In a mining apparatus, a truck having running gear, a self-contained mining machine of a type adapted to slide upon a surface thereof over a mine bottom and provided with a power transmitting element rotating on a longitudinal axis, means for adjustably supporting said machine on said truck for rotation on a horizontal longitudinal axis, and reversible driving gearing for said running gear driven by said power transmitting element and disposed beneath and between the ends of the mining machine.

29. In a mining apparatus, a truck having running gear, a self-contained mining machine of a type adapted to slide upon a surface thereof over a mine bottom and provided with a power transmitting element rotating on a longitudinal axis, means for adjustably supporting said machine on said truck for rotation on a horizontal longitudinal axis coincident with said first mentioned longitudinal axis, and reversible driving gearing for said running gear driven by said power transmitting element and disposed beneath and between the ends of the mining machine.

30. In a mining apparatus, a truck having running gear, a self-contained mining machine of a type adapted to slide upon a surface thereof over a mine bottom and provided with a power transmitting element rotating on a longitudinal axis, means for adjustably supporting said machine on said truck for rotation on a horizontal longitudinal axis coincident with said first mentioned longitudinal axis, and reversible driving gearing for said running gear driven by said power transmitting element and disposed beneath and between the ends of the mining machine, said reversible driving gearing including reversely rotating bevel gears rotating on a transverse axis and selectively operative as the driving element, a longitudinally extending shaft having a bevel pinion meshing with said bevel gears, and a flexible connection between said power transmitting element and longitudinal shaft.

31. In a mining apparatus, a truck provided with running gear, mechanism mounted thereon for rotation on a longitudinal axis including cutting mechanism, a driving motor for said cutting mechanism, and power transmitting means, an actuating shaft for said truck running gear disposed below said rotatably mounted

mechanism and parallel to said longitudinal axis, operative connections between said shaft and power transmitting means, and means for locking said shaft against rotation at will.

32. In a mining apparatus, a truck provided with running gear, mechanism mounted thereon for rotation on a longitudinal axis including cutting mechanism, a driving motor for said cutting mechanism, and power transmitting means, an actuating shaft for said truck running gear disposed below said rotatably mounted mechanism and extending longitudinally of the truck, manually controllable operative connections between said shaft and power transmitting means, and means for locking said shaft against rotation at will.

33. In a mining apparatus, a portable support, a body mounted thereon, a motor carried thereby, cutting mechanism carried by said body and driven by said motor, and means for adjustably supporting said body on said support for rotation about a horizontal longitudinal axis coincident with the axis of said motor including cooperating arcuate guiding means carried by said support and body and including cooperating rollers rotatable on axes disposed in a surface coaxial with the centre from which said arcuate guiding means is struck.

34. In a mining apparatus, a portable support, a body mounted thereon, a motor carried thereby, cutting mechanism carried by said body and driven by said motor, and means for adjustably supporting said body and said support for rotation about a horizontal longitudinal axis coincident with the axis of said motor including arcuate guiding means secured to said body and a plurality of cooperating rollers carried by said support and cooperating with said guiding means.

35. In a mining apparatus, a portable support, a body mounted thereon, a motor carried thereby, cutting mechanism carried by said body and driven by said motor, arcuate guiding members secured to said body for supporting the latter for rotation about its longitudinal axis coincident with the axis of said motor, and cooperating rollers mounted on said support at opposite sides of a vertical longitudinally extending plane passing through the centre of mass of said body.

36. In a mining apparatus, a portable support, a body mounted thereon, a motor carried thereby, cutting mechanism carried by said body and driven by said motor, arcuate guiding members secured to said body for supporting the latter for rotation about its longitudinal axis, cooperating rollers mounted on said support at opposite sides of a vertical longitudinally extending plane passing through the centre of mass of said body.

- body, and means on said support intermediate said rollers and directly engaging said arcuate guiding members for maintaining said arcuate guiding means against vertical 5 displacement with respect to said rollers.
37. In a mining apparatus, a portable support, a body mounted thereon, a motor carried thereby, cutting mechanism and feeding mechanism carried by said body and driven 10 by said motor, said feeding mechanism including a feed operating member rotatable upon a longitudinally extending axis and adapted to cooperate directly with flexible feeding means, and means for permitting 15 adjustment of said body about an axis coincident with the axis of said feed operating member including means for supporting said body on said support including an arcuate guiding means secured to one of 20 the same and cooperating guiding means secured to the other.
38. In a mining apparatus, a portable support, a body mounted thereon, a driving motor carried thereby, cutting mechanism 25 and feeding mechanism carried by said body and driven by said motor, said feeding mechanism including a feed operating member rotatable upon a longitudinally extending axis, and means for permitting adjustment of said body about an axis coincident 30 with the axis of said feed operating member including means for supporting said body on said support including arcuate guiding means secured to one of the same and on the 35 other a plurality of cooperating rollers rotatable on axes disposed in a surface coaxial with the centre from which said arcuate guiding means is struck.
39. In a mining apparatus, a portable support, a body mounted thereon, a motor carried thereby, cutting mechanism and feeding mechanism carried by said body and driven by said motor, said feeding mechanism including a feed operating member 40 rotatable upon a longitudinally extending axis and adapted to cooperate directly with flexible feeding means, and means for permitting adjustment of said body about an axis coincident with the axis of said feed 45 operating member including means for supporting said body on said support including arcuate guiding means secured to said body and cooperating guiding means carried by 50 said support.
40. In a mining apparatus, a portable support, a body mounted thereon, a motor carried thereby, cutting mechanism and feeding mechanism carried by said body and driven by said motor, said feeding mechanism including a feed operating member 55 disposed midway between the top and bottom and between the lateral edges of said body and adapted to cooperate directly with flexible feeding means, and means permitting 60 adjustment of said body upon an axis coincident with the axis of said feed operating member including means for adjustably supporting said body on said support including arcuate guiding means secured to one of the same, and cooperating guiding means 65 secured to the other.
41. In a mining apparatus, a portable support, a body mounted thereon, a motor carried thereby, cutting mechanism and feeding mechanism including a feed operating member disposed midway between the top and bottom and between the lateral edges of said body, and means permitting adjustment of said body upon an axis coincident with the axis of said feed operating member including means for adjustably supporting said body on said support including arcuate guiding means secured to one of the same, and on the other a plurality of cooperating rollers rotatable on axes disposed in a surface coaxial with the centre from which said arcuate guiding means is struck.
42. In a mining apparatus, a portable support, a body mounted thereon, a motor carried thereby, cutting mechanism carried by said body and driven by said motor, arcuate guiding members secured to said body, cooperating guiding rollers mounted upon said support, and means on said support including locking elements directly engaging said arcuate members to prevent longitudinal movement of said body on said support in either direction.
43. In a mining apparatus, a portable support providing means forming a cradle, a body mounted on said support, a motor carried thereby, cutting mechanism carried by said body and driven by said motor, arcuate guiding means secured to said body and supported in said cradle whereby said body may be rotated about its longitudinal axis through substantially a quadrant, and locking means for rigidly connecting said cradle and said arcuate guiding means including locking elements directly engaging the latter in interlocking relation to maintain said body in different adjusted positions.
44. In a mining apparatus, a portable support, a body mounted thereon, a motor carried by said body, cutting mechanism carried by said body and driven by said motor, means for adjustably supporting said body on said support for rotation about a horizontal longitudinal axis including arcuate guiding means secured to said body and cooperating guiding means mounted on said support supporting said arcuate guiding means, and locking means cooperating with said arcuate guiding means including locking elements directly engaging the latter in interlocking relation for maintaining the latter in operative re-

lation about said cooperating guiding means.

45. In a mining apparatus, a portable support, a body mounted thereon, a motor carried by said body, cutting mechanism carried by said body and driven by said motor, means for adjustably supporting said body on said support for rotation about a horizontal longitudinal axis including arcuate guiding means secured to said body and cooperating guiding means mounted on said support supporting said arcuate guiding means, and locking means cooperating with said arcuate guiding means including locking elements directly engaging the latter in interlocking relation for releasably maintaining the latter in operative relation to said cooperating guiding means.
- 10 46. In a mining apparatus, a portable support, a body rotatably mounted thereon, a motor carried thereby, cutting mechanism and feeding mechanism carried by said body and driven by said motor, said feeding

mechanism including a rotatable element, 25 and means for holding said rotatable element against movement relative to said support to permit said motor to react through said feeding mechanism to effect rotation of said body relative to said support. 30

47. In a mining apparatus, a wheeled support, a body mounted thereon, a motor carried thereby, cutting mechanism and feeding mechanism carried by said body and driven by said motor, driving connections between said feeding mechanism and the wheels of said support, means for rotatably supporting said body on said support, and means for rendering said wheel driving connections immovable thereby to cause 40 said motor to react through said feeding mechanism to effect rotation of said body relative to said support.

In testimony whereof we have signed our names to this specification.

GILBERT RIMMER.
AUSTIN YOUNG HOY.
